UNITED STATES PATENT OFFICE.

SAMUEL RAUH, OF NEW YORK, N. Y.

CHILD'S LEGGIN.

SPECIFICATION forming part of Letters Patent No. 365,941, dated July 5, 1887.

Application filed December 13, 1886. Serial No. 221,367. (No model.)

To all whom it may concern:

Be it known that I, SAMUEL RAUH, a subject of the Emperor of Germany, and a resident of New York, in the county of New York 5 and State of New York, have invented certain new and useful Improvements in Children's Draws, of which the following is a specification.

My invention relates to an improvement in 10 children's jersey leggin draws or shields, the object being to provide an article of this kind which shall be so shaped and constructed as to give them a neat appearance. Heretofore the legs of these articles have been constructed with 15 simply one or two seams running the whole length of the leg, giving to the latter an undesirable shape and an unsightly appearance, by reason of which the use of this article of clothing has been very much restricted. In my improved article I provide the leg with two side 20 seams, a front and back seam, whereby I am enabled to impart to the shields a very neat and dressy appearance, overcoming the present objection to their use.

25 In the drawings, Figure 1 is a side view of my improvement. Fig. 2 is a front view of one of the legs, and Fig. 3 is a rear view of the same.

A represents the legs of the draws, made 30 of a suitable fabric, preferably of jersey-cloth, each having two seams, *a*, extending the entire length of the leg. The front side of the leg is also provided with a seam, *b*, and the rear side with a seam, *c*, both of which seams

terminate about midway the length of the leg, 35 allowing the leg to be formed into suitable shape, somewhat similar in shape to the leg of a leggin. The lower portion of the leg is preferably curved outwardly, as shown at *d*, giving to the same the shape of the lower end 40 of trousers, the extreme end being rounded or partially curved up toward the rear side, as shown at *f*.

To keep the legs of the draws in position during use, I provide them with two straps, 45 *e*, which fit below the shoes of the wearer.

It will be readily seen that by constructing the draws with the two side seams, *a*, and cutting the front and rear sides of the lower part of the legs, I am enabled to give them a very 50 neat and suitable shape, adapting them to fit and set perfectly to the wearer.

What I claim as my invention, and desire to secure by Letters Patent, is—

Children's jersey leggin draws or shields 55 constructed with the legs *A* joined at their upper ends, and having side seams, *a a*, running the entire length of the leg, and front and rear seams, *b c*, extending from the lower end of each leg to about midway the length 60 thereof, substantially as shown and described.

Signed at New York, in the county of New York and State of New York, this 6th day of December, A. D. 1886.

SAMUEL RAUH.
